UNITED STATES PATENT OFFICE.

LUKE A. MILEY, OF SEATTLE, WASHINGTON, ASSIGNOR OF ONE-HALF TO
ETHAN A. E. MORRISON, OF SEATTLE, WASHINGTON.

ROTARY ENGINE.

SPECIFICATION forming part of Letters Patent No. 793,207, dated June 27, 1905.

Application filed November 12, 1903. Renewed January 30, 1905. Serial No. 243,348.

To all whom it may concern:

Be it known that I, LUKE A. MILEY, a citizen of the United States, residing at Seattle, in the county of King and State of Washington, have invented certain new and useful Improvements in Rotary Engines, of which the following is a specification, reference being had therein to the accompanying drawings.

This invention relates to rotary engines; and the object of the invention is to produce an efficient reversible engine of inexpensive construction wherein the consumption of steam is reduced to a minimum and the admission of steam may be regulated according to the duty required. I attain this and other objects by the novel construction, arrangement, and combination of the various parts, as will hereinafter be fully described, illustrated in the accompanying drawings, and finally pointed out in the claims.

In the drawings, Figure 1 is an end elevation of an engine constructed according to my invention. Figs. 2 and 3 are transverse vertical sections taken on lines *x x* and *y y*, respectively, of Fig. 4; and Fig. 4 is a substantially horizontal section taken on planes *w w* of Figs. 2 and 3. Fig. 5 is a perspective view of the drum, and Figs. 6 and 7 are similar views of the valve-plugs shown in the sectional views.

Like figures denote corresponding parts in all of the views.

In the drawings, 2 represents the shell or casing of the engine having a removable head 2', belt-passages 3 and 3' for the intake and exhaust, respectively, of the steam, and an outside bearing 5 for the main shaft 6, to which is fastened a rotary or driving drum 7. The drum is provided at each of its ends with an annular collar 8 and arranged longitudinally therebetween; but at opposite sides of the drum are radial pistons 9, having their outer edges flush or even with the peripheries of the collars and the circular wall of the drum-cylinder 4. Cylindrical abutments 10 are fixedly mounted upon shafts 11 and rotated from and at twice the speed of the main shaft by the gear-wheels 12 and 13 upon the said shafts. The abutments are positioned in the casing so

as to contact with the drum the entire distance between the said collars and upon diametrically opposite sides thereof, and to allow the said pistons as they revolve to pass the abutments the latter are each provided with a registering longitudinal incision 14. Located diametrically opposite in each of the said drum-collars and in proximity of the pistons are recesses or pockets 15 and 15', the recesses in one collar being disposed upon opposite sides of the pistons to those in the other collar—that is to say, if the recesses 15 are to the rear circumferentially of the pistons as the drum rotates in a given direction then the other recesses 15' will be in advance of the pistons. Communication is made between the steam-passages 3 and the cylinder through these recesses, passage-ways 16, valve-chambers 17, and ports 18 and 18' and between the exhaust-passage 3' and the cylinder through passage-ways 19, chambers 20, and ports 21, which latter are positioned in the cylinder-wall intermediate the drum-collars. Cylindrical plugs 22 and 23 project longitudinally into the case and through the chambers 17 and 20 and interiorly of the said chambers are cut away and arranged to permit the flow of steam thereby and yet leave segments, such as 24 and 25, to form valves, whereby either or both admission-ports of either pair of chambers may be opened with the closing of the ports in the other pair of chambers and simultaneously close and open the ports of the exhaust-chambers of the respective plugs.

It is obvious from the construction that steam is admitted into the cylinder only while the recesses under the open ports are traveling thereby and that the amount of cut-off and consequent expansion of steam may be regulated by manipulating the valves thereof so as to permit the steam to enter by both ports of each chamber or by one.

It is apparent from the foregoing that the reversal of the engine or drum rotation is accomplished by turning the said plugs sufficiently to change the course of the steam so that it will be admitted through the drum-recesses leading into the annular space between

the drum-collars upon the opposite side of the pistons. The several plugs are connected exteriorly of the case by crank-arms 26 and rods 27, whereby the valves may be operated in 5 unison, as by a lever 28. Provision is made for taking up the wear of the drum to fit steam-tight within the cylinder by boring the latter somewhat conical or diminishing in diameter toward the rear end of the case and turning 10 the drum-surfaces, including the pistons which contact with the cylinder-bore of corresponding taper, and providing a screw 29 to project through a screw-threaded aperture of the head 2', whereby the drum may be moved longitudinally and retained at an adjusted position. The wear of the abutments is compensated by the provision of eccentric bushings 30 and 31 upon the shafts thereof and which upon being turned move the abutments, with their 15 shafts, in the required direction. Stuffing-boxes are included in the invention when necessary to make steam-tight joints where the various parts project through the casing. In order to facilitate the manufacture of the engine and assembling of its parts, the abutment-chambers may advantageously be bored of uniform diameter their entire lengths, and after the drum and abutments are inserted a packing-ring 32 is placed within a registering 20 groove turned in the end of the casing immediately beneath the removable head and contiguous of the cylinder-bore. Spaces 33 are provided at the back of each abutment for the reception of steam to counteract the steam-pressure within the cylinder and acting against 25 the abutments, and by balancing or distributing the steam-pressures acting against the drum the friction of the rotary parts is reduced to a minimum and increased considerably to the efficiency of the engine.

The operation and control of the engine will be apparent from the foregoing and need no further description here. It may be said, however, that various changes may be made 40 in the details of construction without departing from the spirit of the invention or sacrificing its advantages—as, for example, two cylinders may be included in one casing when instead of two abutments for each an intermediate one will serve both cylinders, thus requiring but three abutments. Again, if it is desired to operate the rotary in but one direction then the valve-plugs may be omitted, except when deemed desirable to use them for 45 varying the point of cut-off.

Having described my invention, what I

claim as new, and desire to secure by Letters Patent, is—

1. In a rotary engine, the combination with the casing provided with steam inlet and outlet passages, and an abutment, of a drum having end collars provided with a recess or pocket positioned so as to revolve across the respective ports of said steam-inlet passages, and a piston between said collars, substantially 60 65 as described.

2. In a rotary engine, the combination with the casing provided with steam-passages, a drum provided with end collars and two pistons extending between said collars and positioned upon diametrically opposite sides of the drum, the said collars being provided with pockets those of one collar being disposed upon the opposite side of the pistons to those of the other collar, and valves positioned in the said passages to regulate the admission of steam through the said pockets into the cylinder upon a predetermined side of each piston.

3. In a rotary engine, the combination with the casing having inlet and outlet steam-passages, a drum having end collars provided with pockets and pistons intermediate said collars, and rotatable abutments, of means to adjust the distances between the axes of the 85 drum and the axes of the said abutments such means comprising eccentric bushings rotatably mounted upon the abutment-shafts.

4. In a rotary engine, the combination with the casing having a steam-inlet passage communicating with the steam-cylinder through two ports at some distance circumferentially apart and in proximity of its ends, and steam-outlet passage communicating with the cylinder intermediate the steam-inlets, a drum rotatably mounted within said casing and provided with a piston and collars having pockets therein positioned so as to revolve across the ports of the steam-inlet passages and regulate the flow of steam therefrom, and a valve located in said steam-passage, and means for actuating the valve for opening and closing said ports either independently or together whereby the point of steam admission into the 90 95 said pockets may be controlled.

In testimony whereof I affix my signature in presence of two witnesses.

LUKE A. MILEY.
